INVENTOR

William E. Brock.

BY Francis C. Bowen

ATTORNEY.

UNITED STATES PATENT OFFICE.

WILLIAM E. BROCK, OF PLAINFIELD, NEW JERSEY.

IMPLEMENT FOR VENEERING LUMBER.

SPECIFICATION forming part of Letters Patent No. 476,782, dated June 14, 1892.

Application filed April 24, 1891. Serial No. 390,248. (No model.)

To all whom it may concern:

Be it known that I, WILLIAM E. BROCK, a citizen of the United States, and a resident of Plainfield, in the county of Somerset and State 5 of New Jersey, have invented certain new and useful Improvements in Implements for Veneering Lumber, of which the following is a specification.

My invention is an implement for veneering lumber, as hereinafter fully described, whereby I am enabled to apply a sheet of veneer to a surface of plain lumber, molding, or the like having a tongue-and-groove, rabbet, lap, or other similar joint.

15 In the accompanying drawings, Figure 1 represents a top view of an implement embodying my invention ready to be applied to use. Fig. 2 represents a bottom view thereof. Fig. 3 represents a side elevation thereof. 20 Figs. 4 and 5 each represent a cross-section of a piece of lumber having the veneer applied thereto.

Similar letters of reference indicate corresponding parts.

25 The letter A indicates two rods, which are of cylindrical form, but have their upper and lower central portions flattened to form a suitable bearing-surface for the nuts B of screw-bolts passing through the rods, together

30 with formers D. The rods A are of the same length and the bolts are at similar distances from the ends thereof, while they turn loosely in their sockets. The bolts passing through the formers D are secured on their under surfaces by their heads E. The formers D straddle from one to the other rod A and are flat, except at the ends of their upper surfaces, where they have an upward projection, as more clearly shown in Fig. 3, to prevent the sheet

35 of veneer from being injured while it is being applied to the lumber. The outer edges of the formers D are straight, while the inner edges C thereof have an outline or configuration to correspond with the edges of the piece 40 of lumber, molding, or the like to which the veneer is to be applied. In this example the

45 inner edges C of the formers have central longitudinal grooves or recesses d, extending ap-

proximately the entire length thereof, with overlapping upper and lower portions e, which 50 coincide with the edges of the lumber to be veneered. (See Figs. 4 and 5.) The ends of the formers D are made to taper or curve upward and outward from the bottom to the top thereof, like a plowshare, terminating in the 55 upward projections already referred to. Both ends of the formers D are substantially similar in construction, so they can be moved freely forward and backward over the surface of the veneer when applied to the edges 60 of the lumber, thus forming double-enders.

In order to facilitate adjustment of the formers D on the edges of the piece of lumber to be veneered, I provide a handle J, which by its proper manipulation opens or closes 65 the rods A, and thereby contracts or expands the formers on the edge of the surface to which the veneer is applied.

Referring to Figs. 4 and 5, P indicates a piece of lumber, and T the veneer which has 70 been applied thereto by my implement.

In some cases the formers D may be firmly secured to a rod or rods and brought in engagement with the edges of the dressed article by bringing the rod from a transverse to 75 an inclined position in relation to the article.

What I claim as new, and desire to secure by Letters Patent, is—

1. An implement for veneering lumber, molding, or the like, consisting of rods A, 80 connected with formers D by means of bolts, said formers having their inner edges adapted to fit the edges of the lumber or other article, substantially as and for the purpose described.

2. An implement for veneering lumber, 85 molding, or the like, consisting of rods A, connected with formers D by means of bolts, said formers having their inner edges adapted to fit the edges of the board or other article and the whole provided with a handle for 90 manipulating the same, substantially as and for the purpose described.

WILLIAM E. BROCK.
